Inc., Elkhart, Ind., a corporation of Indiana

Application September 14, 1938, Serial No. 229,952

11 Claims. (Cl. 200—152)

This invention relates to switches, and more particularly is directed to a mercury switch structure capable of use for wall switches, switchboards, and other similar switching applications.

One of the primary objects of the present invention is to provide a compact wall switch structure which can be mounted in a shallow receptacle and which is silent and positive in operation.

Preferably, the present invention employs a metal envelope switch employing a liquid such as mercury for the contacting element, which switch is operated by tilting it in opposite directions to make and break the electrical circuit therethrough. The switch may be of the type shown in detail in the copending application of Paul S. Bear, Serial No. 53,146, filed December 6, 1935, now Patent No. 2,132,921 issued October 11, 1938, although it is to be understood that the construction of the switch itself may vary without in any manner affecting the scope of the present invention.

Another object of the present invention is to provide a switch construction in which the switch itself constitutes both the actuating means and the switching means. For example, in one preferred embodiment of the invention the switch envelope is provided with an insulated extension, which serves as the operating lever or means for tilting the switch and projects through a suitable wall plate opening or the like.

Another feature of the present invention which is of distinct importance is the provision of a switch capable of use as a wall switch, and which is so constructed as to carry appreciably more current than any previous type of switch of the mercury type heretofore employed. With the present construction, switches may be employed for operation in a switchboard or in a wall box or the like which can carry currents up to 200 amperes, although probably the highest currents desired for such installations would not exceed 65 amperes.

A further feature of the present invention is to provide a tilting type switch which may be operated from a two button control, from integral extensions on the switch, or by cam mechanisms connected to an actuating means.

Another advantage attained by the present invention is the provision of a compound switch for opening and closing circuits in multiple or for opening one circuit while closing another, or for controlling any combination of circuits that may be desired. In this connection the

present invention provides a switch construction in which a single actuator may be employed for controlling the operation of a plurality of variably arranged switches which may also be of varying capacities.

Another feature of the present invention is to provide a construction in which a standard type of metal envelope switch of the construction disclosed in said copending application may be employed without any modification of the basic features thereof. This produces distinct economy since it is not necessary to modify this type of switch construction in order to apply it to the particular uses disclosed herein.

Another advantage of the present invention is the fact that the present construction is so designed that it is capable of replacing the conventional type of wall switch now in use to provide a silent operating switch.

Other objects and advantages of the present invention will appear more fully from the following detailed description, which, taken in conjunction with the accompanying drawings, will disclose to those skilled in the art the particular construction and operation of several preferred forms of the present invention.

In the drawings:

Figure 1 is a sectional view through a wall box showing the application of the present switch thereto;

Figure 2 is a front elevational view of the construction shown in Figure 1;

Figure 3 is a top view, partly in section, of the construction shown in Figure 1;

Figure 4 is a modified form of the invention corresponding to the structure shown in Figure 1;

Figure 5 is a front elevational view thereof;

Figure 6 is a detailed view of the actuating extension for the switch;

Figure 7 is a rear elevational view of the bracket by which the switch is mounted in position;

Figure 8 shows a construction in which one or more switches may be employed mounted for operation by push button control;

Figure 9 is a front elevational view of the construction shown in Figure 8;

Figure 10 shows a switch construction for a wall box or the like employing a push-button control;

Figure 11 is a front elevational view thereof;

Figure 12 shows a switch box arrangement for controlling a plurality of circuits of varying sizes by the use of a single actuator which may be em-

ployed to simultaneously control all of the switches.

Fig. 13 is a side view, partly in section of the construction shown in Fig. 12.

Referring now in detail to the embodiment of the invention shown in Figure 1, a wall box is indicated generally at 5 and has the front flanged portion 6 to which the mounting bracket or plate 7 may be secured by means of the screws 8.

The plate 7, as shown more in detail in Figure 3, has at the center thereof two rearwardly extending ears or flanges 9 which are provided with apertured bosses 10 for receiving the trunnions 11 carried at opposite sides of the switch indicated generally at 12. The switch 12 is of the type shown in detail in the copending application referred to above. It comprises a cup-shaped metal envelope having an enlarged end in which is inserted a ceramic insert carrying a disc-like electrode and sealed in the end by spinning over the edge of the cup. Mercury within the switch is adapted to move longitudinally of the switch upon tilting thereof to make and break contact between the metal envelope and the electrode. Suitable structures 13 and 14 are led out from the switch case and connected to a terminal block 15 by means of the terminal screws 16. The switch preferably is enclosed within a two-piece molded casing of insulating material such as described in detail in the copending application of Paul S. Bear, Serial No. 148,946, filed June 18, 1937, and preferably, the portion of the case which encloses the extending end of the switch is provided with an integral extension 17 which may be rectangular in section, and which is preferably serrated as indicated at 18 to project through the opening 19 in the plate 7 and through the rectangular slot 20 in the wall plate 22. Mounted on the extension 17 is an indicating plate 23 which moves upwardly and downwardly with the extension and carries suitable legends thereon for indicating the position of the switch. The wall plate is fastened in any suitable manner such as by means of the screws 24 to threaded bosses on the plate 7 for clamping the same in position with respect to the wall box 5.

It will be apparent that as the extension 17 is moved upwardly and downwardly in the slot 20 in the wall plate, the switch 12 will rotate on its trunnions 11 about the bosses 10 to move from a circuit closed position as indicated in Figure 1 to an opposite angularly extending position with the extension 17 in the lower end of the opening 20, in which position the switch is in its off position. Preferably, the plate 7 is provided with a spring arm 25 having vertically spaced bosses or recesses 26 formed therein which engage a suitable projection 27 on the case of the switch, and act as a detent means for holding the switch in either of its operative positions and for preventing the switch from moving out of its selected position until sufficient pressure is exerted on the extension 17 to snap the projection 27 out of the engaged recess 26 and into the other recess for holding the switch in its opposite limiting position.

While the showing of the switch in Figure 1 indicates that the switch is of considerable longitudinal extent, it is to be understood that if desired the rounded end 28 of the case may itself project through the wall plate 20 with the shoulders 9 being reduced in length so that the pivot point for the switch is moved closer to the plate 7, and thus the rearward extent of the switch

may be materially reduced so that a shallow wall box may be employed.

Considering now the embodiment of the invention shown in Figures 4 to 7, a wall box 30 is provided having the flange portions 32 to which a mounting bracket or plate 33 is secured by means of the screws 34.

The plate 33 is provided on its rear portion with a block member 35 formed of "Bakelite," or some other similar insulating material, which is secured thereto by means of the rivets 36 as illustrated in Figure 4. The member 35 is provided with a recess 37 which flares outwardly toward the rear of the member as indicated at 38. The two side walls of this recess are provided with slot portions 39 adapted to receive the trunnions 40 carried by the insulating extension member 42 fitting over the enlarged end of the switch case 43. The member 42 is provided with a substantially rectangular shaped extension 44 which projects through an opening 45 in the plate 33 and through a rectangular opening 46 in the wall plate 47. The wall plate 47 is secured to the plate 33 by means of the screws in any usual or convenient manner. The switch 43 has the switch case thereof provided with the electrical conductor indicated at 49, which leads to one side of a circuit to be controlled by the switch, and the shank 50 of the electrode carried in the enlarged end of the switch is provided with a conductor 52 leading to the opposite side of the circuit. These leads may be extended out through slots in the extension member or may be passed through suitable openings formed therein as desired, the extension member 42 being axially recessed to fit around the end of the switch and sealed thereto by means of any suitable sealing compound.

Preferably, the member 42 is locked in position, so that the trunnion 40 cannot move outwardly of the slots 39, by means of the locking spring 53 which is snapped into one of the slots in a well known manner. With this form of construction the switch is in its off position when positioned as shown in Figure 4 and is in its on position when the extension 44 is moved downwardly in the slot 46. The extension 44 carries a legend plate 54 corresponding to the plate 23 of the embodiment shown in Figures 1 to 3. The conductors 49 and 52 are preferably connected to suitable terminals 55 and 46 carried in cut back portions 57 and 58, respectively, of the block member 35.

Considering now the embodiment of the invention disclosed in Figures 8 and 9, a wall box 60 is provided to which the mounting plate 62 is secured in any suitable manner such as described heretofore. The plate 62 is provided at its central portion with rearwardly extending shoulders 63 between which is pivotally mounted a bracket member 64 extending rearwardly and having means thereon for mounting a switch 65 in position, the switch being held between a pair of spring-clips 66. The member 64 may also have clips (not shown) extending in the opposite direction for supporting a second switch, indicated in dotted lines at 67, and mounted in a reverse position, whereby one of the switches is in closed circuit position and the other in open circuit position in opposite limiting positions. The member 64 has pivotally secured thereto at opposite ends thereof push buttons 68 and 69 which operate through suitable openings in the plate 62 and in the wall finish plate 70 for move-

ment into and out of the wall box to rotate the member 64 about the pivot point 72 for moving the switches into their opposite limiting positions.

In order to maintain the switches in each of the limiting positions the member 64 is preferably provided with a spring finger 73 which is adapted to engage on opposite sides of a suitable boss 74 carried by one of the shoulders 63. The fingers 73 must be flexed or sprung out of position in order to pass the boss 74, and consequently will hold the switches in either raised or lowered position until sufficient pressure is applied to the desired push button to overcome the resistance offered by the finger against the boss. In the position shown in Figure 8 the switch 64 is in its on position and is connected through the conductors 75 and 76 to a terminal block 77, which in turn is connected into a circuit controlled by the switch 65. On the other hand, the switch 67 may be connected through suitable conductors 78 to a terminal block 79 mounted within the wall box.

Preferably, the terminal blocks 77 and 79 are secured to the plate 62 so that upon removing the wall plate 70 by removal of the screws 80, the plate with the entire switch mechanism may be removed from the wall box by the removal of the bracket plate 62. When the push button 68 is pushed inwardly it moves the push button 66 outwardly and rotates the member 64 about the pivot 72 to move the switches into their opposite inclined position. This results in opening the circuit through the switch 65 and closing the circuit through the switch 67. Obviously, the two switches may be reversed in position or may both extend in the same direction to control two separate circuits simultaneously.

Considering now the embodiment of the invention shown in Figures 10 and 11, a similar wall box 95 is provided to which is secured a bracket plate 96 in the conventional manner, this plate having an opening 97 therein, through which extends the actuating member 98 which, in this form of the invention, is provided at its ends with a hook portion 99. The member 98 within the wall box 95 has secured thereto a camming member 100 mounted for sliding movement on a terminal block member 102 which preferably is formed of insulating material. The camming member 100 has two optional positions within the wall box, the opposite limiting position being shown in dotted lines and being indicated at 100' and 100''. Mounted on a suitable pivot 103 carried by the terminal block 102 is a lever member 104 which has a downwardly curved portion 105 adapted to ride on the inclined surface 106 of the camming member 100. The member 104 is provided with a spring clip projection 107 within which is clamped the switch member 108. The member 108 has its two terminals 109 and 110 connected to the terminal block 102 in any suitable manner, and is adapted to be raised and lowered about the pivot point 103 upon axial movement of the member 98 into and out of the wall box.

When the member 98 is in the position shown, the camming lever 104 is at the lower portion of the cam surface 106 and the member 98 is prevented from moving further outwardly of the box by engagement of the flange portion 111 of the member 100 with the rear of the plate 96. When the member 98 is moved inwardly, the end 105 of the lever 104 rides upwardly on the inclined surface 106 until it reaches the notched

portion 112 into which it drops and thereby raises the switch 108 into the dotted line position closing the circuit through the switch. The engagement of the end 105 of the lever 104 in the notch 112 prevents the actuating arm 98 from moving outwardly until sufficient pressure is applied thereto to raise the end 105 out of the notch 112 over the hump between the notch and the inclined surface 106.

The construction shown in this embodiment of the invention is preferably adapted for use where the switch may be positioned in an out-of-the-way location, and may be controlled from a remote point by means of a rod engaging the hook 98, or may be engaged in any other suitable manner. The "off" and "on" positions of the switch are determined by the location of the arm 98 with respect to the face of the wall plate 114, that is, the arm 98 in switch closed position projects considerably beyond the surface of the wall plate 114, but in switch open position is moved rearwardly substantially to the point at which the hook portion 99 begins. With this type of switch operation it is obvious that in place of the hook portion 99 the member 98 might be made of any desired type in which it is pushed toward the wall for closing the switch, and is pulled out from the wall for opening the switch.

Considering now the embodiment of the invention shown in detail in Figures 12 and 13, in this form of the invention, a multiple operating switch is provided in which a single actuator may be employed for simultaneously controlling a plurality of circuits through a corresponding plurality of switches simultaneously actuated by the single control member.

Within a wall box 120, which may be of any conventional design or which may be mounted on a switchboard or the like, there is a supporting bracket member 122 having a rearwardly extending reversely turned edge portion 123 forming a support for an insulating terminal block 124 which extends transversely of the box 120.

At its forward end the member 122 is provided with an upwardly extending flange portion 125 having an aperture 126 therein through which the actuating rod 127 extends. This rod also passes through an aperture 128 in the forward wall of the box 120. At the lateral sides of the member 122 upstanding ear portions 129 are provided which, at their upper ends, are apertured to receive a transversely extending shaft member 130. Mounted on the shaft member 130 are a plurality of actuating levers 132 which are pivoted intermediate their ends on the shaft member 130 and have downwardly extending forward portions 133 adapted to engage on the cam surfaces of the cam actuator 134 connected as indicated at 135 to the control rod 127.

At their opposite ends the members 132 are provided with clip portions 136 for receiving and supporting the metal envelope mercury switches 137, 138 and 139, respectively.

The member 134 is of a shape similar to the shape of the member 100 described in detail in Figure 10, but has a lower notch portion 142 and an upper notch portion 144 separated by a smooth inclined surface 143. The member 134 extends transversely of the plate 122 so as to be common to all of the levers 132. As shown in Figure 13 the control rod 127 is in a neutral or intermediate position with the ends 133 of the

levers 132 all supported at an intermediate position on the inclined surface 143. Consequently, the switches 137, 138 and 139 are all in an intermediate position between their circuit open and circuit closed positions.

It will be noted that the switches 137 and 138 are of substantially the same size, but are mounted in oppositely extending directions, while the switch 139 is of a larger size, thereby having a greater capacity and able to handle higher currents. The switches 137 and 138 are so mounted as to simultaneously close their respective circuits when tilted in a counter-clockwise direction as viewed in Figure 13, and to close their respective circuits when tilted in a clockwise direction. The switch 139 on the other hand is mounted so as to close its circuit when tilted in a clockwise direction, and to open its circuit when tilted in a clockwise direction. In order to insure proper pressure bearing of the ends 133 of the levers 132 on the cam surfaces, springs 145 are biased between the clip portions 136 of the levers 132 and the upper end of the flange 125 as clearly shown in Figure 13.

It will be noted that when the operating rod 127 is moved to its innermost position, as shown in dotted lines at 127', the levers 132 will all be raised in a counter-clockwise direction and will drop into the notch 142, thus holding the levers in position. This will result in closing of the circuit through the switches 137 and 138 and opening of the circuit through the switch 139. When the control rod is moved in the opposite direction to its outer limiting position, as indicated clearly at 127" in Figure 13, the ends 133 of the levers 132 move downwardly on the cam surface 143 into the notch 140, and consequently effect rotation of the levers 132 in a clockwise direction resulting in opening of the circuits through the switches 137 and 138 and closing of the circuit through the switch 139. Obviously, any number of switches could be employed in this manner, all controlled from a single actuating rod and could be mounted in desired positions for selectively closing and opening circuits upon predetermined action of the rod 127. It will be noted that each of the switches is provided with an enclosing insulating casing through which the lead wires are projected at the large end of the switch and are led down to suitable connections on the terminal block 124 as indicated at 150 in Figure 13. The springs 145 are employed merely to prevent possible freezing of the levers 132 on the shaft 130, and to insure that the lower end of the levers will accurately follow the cam surfaces on the members 134 upon reciprocation of the rod 127. By way of illustration, and not to be taken in any sense as limiting, the switches 137 and 139 shown in Figure 12 are of a size capable of handling 20 amperes, while the switch 138 is of a size capable of handling 35 amperes. These switches are drawn substantially to scale in this particular illustration. However, switches handling up to 65 or 100 amperes may be readily incorporated in such a structure. Referring back again to Figures 1 to 7, inclusive, it will be noted that in this particular application of the switch to a wall box construction, the switch covering itself is employed as the actuating means for controlling the rotation of the switch.

In the other embodiments of the invention, ancillary actuating means is provided such as the two push-button control shown in Figure 8, or

the cam operating wedge shown in Figures 10 and 12. In all forms of the invention it is to be understood that suitable detent means is provided for insuring that the switch will be held in each of its actuated positions, such as shown at 26 in Figure 1, or as shown at 73 in Figure 8, or 152 in Figure 13.

It is therefore believed apparent that we have provided a novel type of wall switch construction, which may be employed for domestic purposes, such as in homes, restaurants, apartments, or the like, or which may be designed for carrying heavier loads and used in switchboards or other installations for industrial switching purposes.

While the invention has been described and illustrated in connection with several preferred means of applying the same for such applications, it is readily understood that changes in details of the design and construction can be made without departing from the underlying principles of the invention, and the invention is therefore not to be limited except as defined by the scope and spirit of the appended claims.

We claim:

1. A wall switch comprising a wall box, a bracket secured thereto and having laterally spaced ears extending into said box, a metal envelope mercury switch, an insulating case for said switch having integral trunnions pivotally mounting said switch for tilting movement between said ears, said insulating case enclosing said switch and having an integral extension on one end projecting outwardly of the box between said ears for moving said switch from one tilting position to another.

2. A wall switch comprising a wall box, a bracket secured thereto and having ears extending into said box, a metal envelope mercury switch disposed entirely within said box and having an enclosing insulating shell provided with trunnions pivotally mounting the same between said ears for longitudinal tilting of said switch, and an insulating extension integral with one end of said shell and projecting outwardly through said box for actuating said switch.

3. A wall switch assembly comprising a wall box, a bracket plate secured to the front face thereof, transversely spaced ears on said bracket within said box, a metal envelope mercury switch disposed entirely within said box and having an insulating enclosing case, trunnion means formed on said case for pivotally supporting said switch intermediate its ends between said ears, a flush plate secured over said bracket and having a rectangular slot therein, and an integral longitudinal extension on one end thereof said case projecting outwardly of said box through said slot and vertically movable therein for tilting said switch.

4. A wall switch assembly comprising a wall box, a bracket plate secured to the front face thereof, transversely spaced ears on bracket within said box, a metal envelope mercury switch disposed entirely within said box and having an insulating case, trunnion means formed on said case for pivotally supporting said switch intermediate its ends between said ears, a flush plate secured over said bracket and having a rectangular slot therein, an integral longitudinal extension on said case projecting through said slot and vertically movable therein for tilting said switch, and a spring detent arm on said bracket plate between said ears and an integral detent

engaging boss on the case for holding said switch in opposite tilted positions.

5. A wall switch assembly comprising a wall box, a bracket plate secured to the open face thereof and having laterally spaced ears within the box, an insulating actuator pivotally supported between said ears within the box and having an actuating portion extending outwardly through the bracket plate, and a metal envelope mercury switch entirely enclosed in said actuator within said box, said actuator being rocked in opposite directions about its pivot to tilt said switch means in opposite directions for selectively controlling a circuit through said switch.

6. A wall switch assembly comprising a wall box, a bracket secured to the open face thereof and having laterally spaced slots within the box, an insulating actuator having a chambered portion pivotally supported in said slots within the box and having an actuating portion extending outwardly through the bracket plate, spring means in said slots holding said actuator against sliding movement relative thereto, and metal envelope mercury switch means supported in the chambered portion of said actuator, said actuator being rocked in opposite directions about its pivot to tilt said switch means in opposite directions for selectively controlling a circuit through said switch, said bracket plate having means cooperating with said actuator for resiliently maintaining said actuator in each of its switch controlling positions.

7. In combination, a wall box, a bracket plate secured to the open face of said box and having an insulating member supported on the inner face thereof, an aperture through said member and plate, opposed slots extending axially from the inner end of said aperture toward the outer end thereof, a metal envelope mercury switch having an enlarged end portion, an insulating cup-shaped member receiving said enlarged end and having trunnions for supporting the same in said slots, and an integral extension on said cup-shaped member projecting from said box for tilting said member about said trunnions.

8. In combination, a wall box, a bracket plate secured to the open face thereof and having

laterally spaced ears within the box, a metal envelope mercury switch having an enlarged end, an insulating case enclosing the entire switch and having integral trunnion like projections at the enlarged end portion of the switch, said projections being pivotally supported in said ears, and an integral extension projecting longitudinally of the case out through an aperture in said bracket plate for rocking the switch in opposite directions.

9. In combination, a wall box, a bracket plate secured to the open face of said box and having an insulating member supported on the inner face thereof, an aperture through said member and plate, opposed slots extending axially from the inner end of said aperture toward the outer end thereof, a mercury switch including an insulating case having opposed trunnions supporting the switch for tilting movement in said slots, and an extension on one end of said case projecting from said box through said bracket plate for tilting said switch about said trunnion.

10. In combination, a wall box, a bracket plate secured to the open face of the box and having a tubular extension into the box, laterally aligned slots in the inner wall of said extension opening into the inner end thereof, a mercury switch of the tilting type within said box, an insulating actuator extending through said extension having a chamber receiving said switch and having trunnions pivotally supported in said slots, and means locking said trunnions against movement axially in said slots.

11. In combination, a wall box, a bracket plate secured to the open face of said box and having an insulating tubular member secured to the inner face thereof, a pair of laterally aligned horizontal slots in the bore of said member adjacent the inner end thereof, mercury switch means including an insulating actuator trunnioned in said slots and having a projection extending outwardly through said plate, and means engageable in said slots locking said actuator trunnions against axial movement therein.

PAUL S. BEAR.
HERBERT E. BUCKLEN.
